CIGAR MACHINE

John F. Halstead, Brooklyn, N. Y., assignor to
 International Cigar Machinery Company, a
 corporation of New Jersey

Application December 22, 1936, Serial No. 117,180

59 Claims.

(Cl. 131—21)

This invention relates to cigar machines, and more particularly to bunch making mechanism, and especially to charge forming devices therefor.

In certain types of fresh work or long filler cigar machines heretofore in use it has been customary to feed the filler tobacco by means of a feeding mechanism which included a feed channel having spaced belts for maintaining the tobacco fed in a stream of constant width, cut it into sections of predetermined length, and then feed the cut sections to bunch charge measuring and cutting mechanisms. Due to the abutting arrangement of the lengths being advanced to the cutting mechanism, bunch charges were often formed partly from one section and partly from an abutting section, which sometimes resulted in the presence of "strings" or undesirable slivers of tobacco in the bunch charge. At times it has also been rather difficult to produce bunches free from longitudinal side depressions which may be formed when relatively thick charges are rolled into bunches. A possible cause of this is that the edges of this type of charge must be brought together in the loop of the Chianti belt in an attempt to make the bunch assume as round a form as possible. Nevertheless with all this effort some bunches have had these longitudinal depressions along their sides.

The speed and skill of the operator in placing leaves in the feed mechanism have been important factors in the rapid formation of bunches, since variations in the height of tobacco issuing from the feed have been reflected in the thickness of the lengths cut from the stream of fed tobacco, and have had an effect upon the uniformity of the bunches formed from this tobacco.

In the present invention the personal element has a substantially lessened effect upon the uniformity of the charges being formed. While well known types of feed mechanisms may be used, means for assuring uniform charges have been provided such that each bunch charge will be substantially unvarying with the next formed. This has been accomplished by feeding lengths of tobacco cut from the stream of tobacco coming from the feeding mechanism into a magazine in superposed position, compressing these lengths to form a column of uniform density and separating from this column thin sections of tobacco of a size sufficient to make a bunch. Accordingly it is an object of this invention to provide mechanism for forming more uniform bunch charges than has heretofore been possible.

It is also a further object of the invention to provide means for feeding long filler tobacco into

5 a magazine in individual lengths in superposed position and to separate therefrom layers of tobacco of a quantity necessary to make bunches of a predetermined size.

- 5 It is a further object of the invention to provide feeding means for feeding lengths of tobacco from a stream or other source of tobacco without depending upon uniform thickness of the lengths, stack these lengths individually to form 10 a column, compress the column to a uniform density, and then separate therefrom thin sections of tobacco of cigar bunch size, capable of forming more perfectly rounded and uniformly filled cigar bunches.
- 15 It is an added object of the invention to lay tobacco leaves in a feed mechanism in substantial parallelism one with another to form a stream of tobacco, cut lengths from this stream, feed the lengths into a confining space, and at 20 all times retain the substantial parallelism of the leaves until bunch charges separated from said space are rolled into bunches.

It is a further object to provide bunch charge forming mechanism which will form thin wafer 25 like bunch charges which are of the order of ten times, more or less wider than they are thick, and which will allow rolling into more perfect bunches. It is a further object to provide means for overcoming any disadvantages incident to 30 rolling bunch charges of approximately two to one proportions in width and thickness, as in the old method, and instead provide bunch charges of definitely greater width than thickness.

- 35 In view of the novel charge forming mechanism of the present invention the speed at which bunch charges may be produced is greatly increased due chiefly to the fact that filler tobacco need not be placed in the feed mechanism with 40 so great care as formerly required. Therefore it is an object to speed up the production of bunch charges while at the same time obtaining a uniformity of charge hitherto unobtainable, and making it possible to increase the output 45 of the cigar machine of which this structure forms a part.

It is also an object of the invention to eliminate so far as possible cutting and breaking the 50 leaves which are to make up the bunch charges. Therefore, according to this invention sections of leaves of proper length are cut from a stream of tobacco, associated with other sections in a column in superposed relation, and the desired quantity of tobacco for a bunch charge is cut

from this column with a minimum of damage to the leaves.

It is a further object of the invention to feed long filler tobacco in laminated formation into a magazine, form a vertical column of superposed laminations of leaves, and separate thin sections from said column with a minimum of cutting and breakage of the leaf structure.

A further object is to utilize the full width of the leaves which are fed into a column forming magazine with no further cutting at right angles to their level, and separating charges therefrom and in which the charge is cut parallel with the leaf layers of the column with little or no breaking up of the leaves, hitherto the main detriment to wide cuts for long filler tobacco bunch charge forming means.

The invention also consists in the provision of transfer mechanism into which thin layers of tobacco separated from the charge forming column are delivered for transfer to a bunch rolling mechanism.

The invention also consists in the provision of transfer mechanism into which thin layers of long filler tobacco are placed and conveyed into a bunch making device where the layers are discharged still substantially in intact layer form into a loop in the Chianti belt of said device, in which belt the layers are thereupon rolled into bunches. This novel method of bunch forming effectively eliminates unevenness in the bunches and the formation of "channels" sometimes encountered when bunch charges cut according to the old method are transformed into bunches.

The invention also consists of means for feeding long filler tobacco in a stream, means for cutting predetermined lengths from said stream and delivering them into a magazine, a device for compacting the tobacco in said magazine to a predetermined density, means for separating thin layers from the tobacco in the magazine, means for interrupting the feed mechanism to prevent further feeding of the tobacco stream when an adequate supply of tobacco is present in the magazine, and means for rehabilitating said feed to feed additional tobacco to said magazine.

To the accomplishment of these and other objects not specifically mentioned in view, one embodiment of the invention resides in the construction and arrangement of parts hereinafter more fully described, illustrated in the accompanying drawings and defined in the appended claims.

In the accompanying drawings which form a part of this specification and in which like characters of reference indicate the same or like parts:

Fig. 1 is a perspective view of an embodiment of the invention illustrating the manner in which the filler is fed, cut and transferred to the rolling table where it is combined with a binder to form a cigar bunch;

Fig. 2 is a side elevation of a bunch feeding mechanism including a thin charge separating and cutting device, transfer and rolling units constructed in accordance with my invention;

Fig. 3 is an end elevation of the rolling table showing its central slidable mounting and an adjustable belt roller;

Fig. 4 is a side elevation of the mechanism for regulating the size of the bunch charge;

Fig. 5 is a side elevation of the self-closing transfer device in receiving position with an intermediate and final delivery position indicated in dot and dash lines;

Fig. 6 is a front view of the structure shown in Fig. 5 in its receiving position;

Fig. 7 is a side view of the charge separating and cutting device;

Fig. 8 is a plan view of the device shown in Fig. 7 with one of two extreme positions indicated by dot and dash lines;

Figure 8a is a partial elevational view of the means for reciprocating the knife cutter bar;

Figure 8b is a sectional view of the means for reciprocating the knife cutter bar;

Fig. 9 is a fragmentary perspective view of the reciprocating blade showing its mounting in the bracket arm and location in the separating plate;

Fig. 10 is a side view of the filler magazine, partially in section, showing the thin charge being separated from the filler supply with some related mechanism shown in the loading position as indicated by dot and dash lines;

Fig. 11 is a sectional view of the magazine showing the loading of the same before it is lowered into charge-separating position;

Fig. 12 is a section taken on line 12-12 of Fig. 10, showing a thin charge being separated; and

Fig. 13 is a fragmentary side view of the cross feeding mechanism control.

In the embodiment selected to illustrate the invention, there is provided a loading platform where the filler is received in a stream from a cross-feeding or other suitable feeding mechanism, then cut to lengths and moved by a conveying device moving back and forth over said platform into a magazine. Means is provided for compacting the superposed lengths or laminations of long filler in the magazine and positioning it for the operation of a separating mechanism which in this embodiment includes a movable knife blade operating in conjunction with a relatively thin plate to separate a charge from the filler supply of the magazine. This charge is delivered by a suitable conveyor into a transfer device and is retained thereby as it is swung down to be transferred to the rolling table on which the binder is applied to produce a cigar bunch.

Referring to Figs. 1 and 2, the filler charge feeding and charge separating mechanism is mounted on the frame 11 of a cigar machine. Brackets 12 and 13 bolted to the frame 11, support plates 14, 15 and 15a, suitably secured thereto, as at 16 which form the side walls of a filler supply magazine 17. A pressure plate 18 (Fig. 12) secured at 19 to a slide 20, mounted in grooved projecting guides 21 of a bracket 22 and retained by plates 23 attached thereto at 24, is operated to compress and guide the column of filler tobacco which is held in the magazine 17 by a bottom plate 25. The bracket 22 bolted to the side of the plate 14 provides bearings for a shaft 26 upon which is fixed a lever 27 (Fig. 12). A slide operating link 28 is pivoted to the lever 27 at 29 and to the slide 20 at 30. A lever 31, fixed to the shaft 26 and provided with a rod 32 suitably attached thereto at 33 which rod supports a weight 34, adjustably located along its length, as at 35, is actuated by a pin and slot connection 36 to a cam-operated link 37. The shaft 26 is connected at its other end to a cross feed control mechanism (Figs. 1 and 13) which may be of the type shown in the patent to Bronander No. 1,740,571, granted December 24, 1929, which will prevent any additional filler being fed by the cross feed when an amount over a predetermined surplus exists in

the magazine 17. The magazine bottom plate 25 is attached, as at 38, to a bracket 39 which projects from a grooved slide member 40, adapted for vertical travel on a slide 41 (Figs. 2, 10 and 12), retained therein by a plate 42 suitably attached at 43. The slide 41 is mounted on the bracket 12 (Fig. 2) and extends upward to the grooved slide member 40 which is connected to a cam-operated link 44 by a pin 45 guided in a slot 46 thereof. A sliding block 47 (Fig. 4) curved at one end to fit the pin 45, is fitted to the slot 46 of the link 44 where a spring 48, located on a stud 49, secured to the other end of the block 47 and passing through the top of the link 44 yieldingly holds it in a position limited by nuts 50 on the stud 49. This feature in cooperation with a stop to be described permits of adjustment for different thickness of charge such as indicated at C' (Fig. 10).

When the tobacco filler T is fed through the belt-formed channel 51 of the feed mechanism (Fig. 2) which may be of the type above referred to, it is cut into bunch lengths T' on a platform 52 by a cutter 53, both having corrugations 54 for shaping the bunch ends while the platform 52 is in a horizontal position. The platform 52, mounted on an arm 55 which is fixed on a shaft 56 is lowered by a link connection 57 (Figs. 1 and 2) to a cam (not shown) similar to that shown in the Bronander patent referred to into an inclined position while a pair of transfer guide arms 58, also mounted on the shaft 56 are positioned to retain the bunch lengths T' on the platform 52, before it is lowered, by a link 59 connected to a cam (not shown), by mechanism of the type shown in the Bronander patent. The platform 52 in its inclined position rests on a gate or closure member 60 which projects over the space between the magazine wall plates 14 and 15, and a swinging rake 61, a plate 62 of which is notched at 63 (Fig. 1) to coact with the guide arms 58, draws off the severed bunch lengths T'. The plate 62 of the rake 61 which may have a suitably beveled edge for effective operation on both the platform 52 and gate 60, forces the filler section or bunch length into position directly over the space between the magazine wall plates 14 and 15. In doing so, the rake 61 advances slightly beyond a position of alignment with the magazine wall plate 15 which it occupies when the magazine bottom plate 25 is released and then returns. In this manner each length fed to the magazine will be compacted laterally by the members 14 and 62 before it is associated with the tobacco in the magazine.

Links 37 and 44 are connected at 63 and 64 respectively to cam levers mounted at 65 which are provided with followers for coaction with cams 66, mounted on shaft 67.

With the filler section T' or severed bunch length in place on the member 60 in the magazine 17 the cam-operated link 37 is lowered permitting the weighted lever 31, at its pin and slot connection 36 to descend with the pressure plate 18 bringing it to bear against the filler section T' supported on the member 60. Simultaneously, the link 44 is raised allowing the slide member 40, at its connection thereto at 45 to travel upward, with any surplus filler supply carried on the magazine bottom plate 25, under the influence of a spring 68 (Figs. 2 and 4) supported between the plate 14 at 69 and the slide member 40 at 70. The compressed filler section T' now held by the member 60 which lies between any surplus filler that has been brought up by the

bottom plate 25 (Fig. 11) is released and the entire filler supply is lowered into position for the separation of a thin charge when the member 60 has been retracted. A block 71 (Figs. 2 and 10) fastened to the member 60 at 72 is provided with holes for two rods 73, which are secured to the magazine plate 15 and the member 60, thus slidably supported, is retracted from its position over the magazine 17 by a link 74 pivotally connected at 75 to the block 71 and to a lever 76 at 77. The lever 76 is fixed on a shaft 78 journaled in a bracket 19 on the frame 11 and is operated by one of the several cams 66 on the shaft 67 through operating connections 80, 81 and 82 (Fig. 2). During the time cam-operated links 37 and 44 are actuated to bring the pressure plate 18 and magazine bottom plate 25, together with the filler supply, down into charge separating position, a pin 83 (Figs. 4 and 11) on the bracket 39 of the slide member 40 engages an adjustable stop plate 84 pivoted on the bracket 12 at 85. A set screw 86 and a nut 87 supported on a lug 88 of the bracket 12 retain the position of the plate 84 against the action of the pin 83 at 89, in this manner providing for a predetermined thickness of the charge to be separated. The sliding block 47 previously described as fitted to the slot 46 of the link 44 and yieldingly held in position by the spring 48 will be raised, compressing the spring 48 by the additional travel of the link 44 since the magazine bottom plate 25 and slide member 40 have come to rest, as described.

With the filler supply in the form of a column of superposed filler lengths in the magazine, a charge separating mechanism 90 above the magazine bottom plate 25, slidably supported on two rods 91 secured to the magazine plate 15 and passing through a block 92 is operated by one of the several cams 66 with connections thereto similar to those provided for the closure member 60. A separating plate 93 is attached to the block 92 at 94 and a reciprocating bar 95 with two rollers 96, pivoted thereon at 97, is fitted to angularly opposed slots 98 in the block 92. A knife blade 99 which in the illustrated embodiment is shown provided with a serrated cutting edge, is fitted in horizontally slotted ends of bracket arms 100 and is held in place by pins 101 on the blade 99 which are positioned in vertical slots 102 of the arms 100.

The bracket arms 100 are attached to the reciprocating bar 95 at 103 (Fig. 8) to permit of tension adjustment for the knife blade 99 as provided by bolts 104 and nuts 104a mounted on the bar 95. The knife blade 99 is reciprocated horizontally in a slot 105 of the separating plate 93 as the charge separating mechanism 90 is advanced into the filler supply by operation of a link 106 connected to the block 92 at 107 and pivoted to one arm of a bell-crank lever 108, at 109 which is actuated on the shaft 78 by one of several cams 66 through connections similar to 81 and 82. The separating plate 93 is tapered at its effective edge 110 to facilitate the cleavage of the compressed tobacco leaves in the filler supply as it follows the knife blade 99 which in its cutting motion from side to side has cut only the upturned stems or other leaf obstructions that are not substantially parallel as a part of the laminated tobacco supply. The full width of the leaves has been retained as there has been no further cutting at right angles to the level of the leaves since fed from the cross-feed onto the plate 52, and hence breakage and damage to the leaves is held at a minimum. Also this

work of charge forming is responsible for the absence of slivers of tobacco or "strings" commonly present in charges produced by other methods heretofore referred to. The cutting motion described by the reciprocating knife blade 99 is effective to cut only as it advances toward the center of the filler supply which it clears upon its return stroke. Similar conditions will obtain at both ends of the zig-zag travel of the knife blade 99 due to the opposing angles of the slots 98 engaged by the rollers 96. This method of cutting toward the center of the filler supply eliminates any possibility of pulling out fragments of the leaves or damaging the ends previously shaped by the cross feed cutter 53. As a result a thin charge "C" of whole leaves is separated with a minimum of cutting or damage. In the illustrated embodiment bar 95, which supports blade 99, is reciprocated by means of motor M mounted on frame 11 of the machine (Fig. 2). Fixed to the motor shaft is a collar 112b upon which is eccentrically and pivotally mounted at 112a a connecting fork member 111b. Attached to one end of this member, and extending to the forked portion at the other end thereof, is a rod 111 which is secured to bar 95 (Figures 8, 8a and 8b).

A plunger plate 113 (Figs. 2 and 10) to which a plunger 114 is suitably secured at one end, is slidably supported on two rods 115, secured to a magazine plate 15a and passing through a block 116 attached to the plunger plate 113 at 117. Plunger 114 may be provided in various thicknesses or be adjustable to various thicknesses. A link 118 connected to the block 116 at 119 and to one arm of a bell-crank lever 120 at 121 mounted on the shaft 78 is operated by one of several cams 66 with connections similar to 80, 81, 82 provided for the operation of the gate 60. When the thin charge C has been separated the plunger plate 113 with its plunger 114 travels between the separating plate 93 of separating mechanism 90 and the magazine bottom plate 25 to force the separated thin charge C between relatively separable members of a swinging transfer device 124 (Figs. 5, 6 and 10) which in the embodiment shown comprises plates 122 and 123 hinged together at 125 and held open to receive it by the magazine bottom plate 25 engaging a ledge 126 formed on plate 123. The plunger plate 113 is retracted after loading the transfer device 124 and the magazine plate 25 is elevated to a suitable distance from the separating plate 93 so that the remaining filler supply will be supported after the separating mechanism 90 is retracted. The plate 122 is suitably secured to a bracket 127 fixed on a shaft 128 and which carries two arms 129 and 130 to coact with a pin 131 mounted on a block 132. The block 132, together with a plate 133, one part of which is upturned at 134 and another part turned down at 135, is attached to the plate 123 at 136. A lug 137 on the bracket 127 carries a pin 138 from which a spring 139 is attached to a pin 140 on the downwardly extending lug 135 which spring normally tends to draw plate 123 towards plate 122 into layer holding position. A slotted cam arm 141, integral with the bracket 127 is operated on its coacting follower 142, pivoted on an arm 143 (Fig. 2) attached to the bracket 12 at 16 and is caused to swing by a cam operated lever 144. The lever 144 pivoted at 145 on the bracket 12 and loosely mounted on the shaft 128 is attached to a link 146 at 147 which is operated from one of the several cams 66. As the transfer device 124

swings down (Fig. 5) the plate 123 moves from its contact through ledge 126 with plate 125 and is urged by the spring 139 to close and retain the thin layer of tobacco or charge C until the arm 129 strikes the pin 131 and forces the plates 122 and 123 as far apart as the upturned lug 134, acting as a stop, will permit. The spring 139 cooperates and maintains this position while the charge is delivered to a rolling table 148 below. 10 In the lowermost position of the transfer member, plate 123 thereof comes to rest against a side of the loop or pocket of the rolling apron or Chianti belt which is about equal in depth to the width of the layer. Then as arm 129 strikes pin 131 and forces the plates apart against the tension of spring 139 the thin section transferred to the loop will slide out of the transfer member and rest substantially on the side of the loop so that as the transfer device rises and leaves the section in the loop, the section may remain substantially intact and upon the forward movement of the rolling pin 163 the section is rolled up and formed into a cigar bunch. Later, as the transfer device is restored to its receiving position the arm 130 acts upon the pin 131 to return the plates 122 and 123 to normal unloaded position in which plates 122 and 123 are held by the above mentioned means yieldingly together at their free ends until contact of ledge 126 with plate 25 again opens the transfer member for reception of a new charge.

The rolling table 148 is centrally mounted on a base 149 so shaped as to permit a swinging roller bracket 150 to be pivoted midway its height by the medium of a link 150a to a sliding bracket 151, as at 152 and 153. Rails 154 suitably secured to the base 149 and fitted to the bracket 151 provide for the sliding movement of the roller bracket 150 and will maintain it at all times steadily level so as to correct the irregularities in the filler charge and produce bunches of more uniform body. The sliding bracket 151 is pivotally connected at 155 to a link 156 the other end of which is pivoted at 157 to a cam-operated lever 158. A link 159 secured in a slot 160 at 161 is actuated by a cam (not shown) to operate the roller bracket 150 in the well known manner. A belt 162 is attached and adapted to be stretched between a roller 163 on the bracket 150 and a roller 164 adjustably mounted on the brackets 12 and 13 to cooperate in the usual manner with the rolling table to produce a cigar bunch of the thin charge. Rollers 165 pivoted on the bracket 150 and link 150a are adapted to slide in a grooved plate 166 attached to the frame 11 and cooperate with the rails 154 in the operation of the rolling bracket 150.

The cross feeding mechanism (Fig. 13) which may be of the type shown in Patent No. 1,740,571 issued December 24, 1929, to Wilhelm B. Brolander, is intermittently driven by a ratchet 167 mounted on a shaft 168 as long as it is engaged by a double pawl 169 pivoted at one end of a lever 170, at 171. The lever 170 on the shaft 168 is oscillated by an arm 172 fixed thereto at 170a and slidably secured by a pin 173 (Fig. 1) in a slot 174 to a crank 175 on the shaft 176. A stop screw 172a mounted on the arm 172 limits the movement of the pin 173 for adjustment of the feeding stroke. A sprocket 177 on the shaft 176 is driven by a chain 178 from a sprocket (not shown) on the main shaft of the machine. An arcuate arm 179 mounted at 180 to a releasing lever 181 provides for movement of the double pawl 169 into or out of engagement with the

ratchet 167 by coaction with a roller 182 mounted on the pawl 169. The releasing lever 181 pivoted at 183 to the frame 11 is held at 184 to keep the arm 179 raised and the pawl 169 out of engagement with the ratchet 167 by a locking lever 185 notched at one end and pivoted on the frame 11 at 186. Springs 181a and 185a, suitably secured to levers 181 and 185 at 187 and 188 respectively, are anchored on the frame 11 at 189. The lever 185 is operated by a crank arm 190 on the shaft 26 through a link 191 pivoted to the crank arm 190 at 192 and secured to the lever 185 by a pin and slot connection 193. A forked adjusting lever 194 is pivoted on the shaft 26 and is provided with screws 195 which bear against a pin 196 on arm 190. An adjustable screw 197 is secured in a bracket 198 attached to the cross feeding frame 199 to limit the travel of the arm 172 and the double pawl 169 in one direction. A stop pin 200 is provided on the frame 11 for limiting the travel of the pawl 169 in the opposite direction.

When the height of the accumulated mass of tobacco in magazine 17 reaches a predetermined level, downward movement of weight 34 is stopped, and shaft 26 is prevented from rocking an amount sufficient to operate the lever 185 and permit the spring 181a to move the lever 181 so that the pawl 169 may engage the ratchet 167 for feeding.

To prevent accidental engagement of the pawl 169 at some point during the forward stroke of the crank 175 which would result in a short charge being delivered to the platform 52 a bell crank lever 201 is pivotally mounted on the frame 11 at 202 and one arm 201a, notched to engage the end of the arcuate arm 179 holds it in position to prevent the pawl 169 from engaging the ratchet 167. The larger arm 201b of the lever 201 operates by gravity to position the arm 201a as described until the crank 175 in its rotation strikes it up at a time coincidental with the release of the pawl 169 for engagement by operation of levers 181 and 185.

The various means referred to may be varied in construction within the scope of the claims for the particular structure selected to illustrate the invention is but one of many possible concrete embodiments of the same. The invention is not, therefore, to be restricted to the precise details of the structure shown and described.

What is claimed is:

1. In a cigar machine, a conveyor, a cross feed mechanism for feeding a tobacco stream onto a conveyor, a cutter for cutting predetermined lengths from said tobacco stream as it issues from said mechanism onto said conveyor, means for lowering said conveyor, a vertical tobacco magazine having vertical sides and an open top, a gate for closing said top, means for locating a length of tobacco on said gate over said magazine while said top is closed, means for raising tobacco in said magazine against said gate, means for withdrawing said gate and thereby allowing said length to enter and assemble with tobacco already in said magazine.

2. A cigar machine comprising a tobacco feed mechanism for feeding a stream of tobacco leaves or particles, a vertically movable support onto which tobacco is fed, means for severing predetermined lengths from said tobacco stream after it is fed onto said support, means for lowering said support, a vertical magazine for holding a plurality of superposed lengths of tobacco, means for feeding a length into said magazine from

said lowered support with the tobacco leaves (or particles) thereof arranged (or positioned) substantially relatively as to each other as originally cut from the stream, means for separating a uniform charge of tobacco from the bottom of the tobacco in said magazine, a bunch charge receiving transfer member, and means for ejecting said separated charge from said magazine into said member.

3. In a cigar bunch machine, the combination with a vertical open end magazine having a receiving and a discharging end, of charge measuring and separating means for separating a predetermined volume of tobacco at the discharge end of said magazine, a tobacco feed for advancing a stream of long filler tobacco leaves or particles, a movable support positioned to receive a length of the advancing end of said stream equal to the length of a bunch, a cutter for severing said length from the remainder of the stream, means moving said support out of alignment with the feed into position to deliver into the open receiving end of said magazine, a pusher having to and fro movement along said support to push said length into said magazine with the tobacco leaves (or particles) thereof substantially arranged (or positioned) relatively to each other as originally cut from the stream to fill the magazine with laminations comprising a plurality of superposed lengths, and a vertically reciprocating plunger movable into said magazine to compress said laminations during charge severing operation.

4. In a cigar bunch machine, the combination with a vertical open ended magazine having a receiving and a discharge end, of charge measuring and separating means for separating a predetermined volume of tobacco at the discharge end of said magazine, a cross feed for advancing a stream of long filler tobacco, a movable support positioned to receive a length of the advancing end of said stream equal to the length of a bunch, a cutter for severing said length from the remainder of the stream, means moving said support out of alignment with the cross feed into position to deliver into the open receiving end of said magazine, a closure member for said opening onto which lengths are delivered, means for pushing said lengths onto said member, means for withdrawing said member and allowing said lengths to enter said magazine, and means for interrupting said feed when said magazine contains a surplus of tobacco.

5. In a cigar bunch machine, the combination with a vertical open ended magazine having a receiving and a discharge end, of charge measuring and separating means for separating a predetermined volume of tobacco at the discharge end of said magazine, a feeding device for feeding a stream of long filler tobacco, a movable support positioned to receive a length of the advancing end of said stream equal to the length of a bunch, a cutter for severing said length from the stream, means moving said support out of alignment with said device into position to deliver into the open receiving end of said magazine, a gate closing said opening, means for pushing said lengths onto said gate, means for withdrawing said gate and allowing said lengths to be fed into said magazine, said measuring and separating means including a reciprocating carriage, a plate, and a knife mounted on said carriage, and means for moving said carriage so that said plate separates a predetermined thick-

ness of tobacco from said tobacco in said magazine.

6. In a cigar bunch machine, the combination with a vertical open ended magazine having a receiving and a discharge end, of charge measuring and separating means for separating a predetermined volume of tobacco at the discharge end of said magazine, means for forwarding a stream of long filler tobacco, a movable support positioned to receive a length of the forward end of said stream equal approximately to the length of a bunch, a cutter for severing said length from the remainder of the stream, means moving said support out of alignment with the forwarding means into position to deliver into the open receiving end of said magazine, a gate closing said opening, means for pushing said lengths onto said gate, a movable platform in said magazine supporting said tobacco, means for raising said platform to press the tobacco in said magazine against said gate, and means for withdrawing said gate to allow the tobacco positioned thereon to assemble with the tobacco in said magazine.

7. In a cigar bunch forming machine, a feed mechanism for feeding a stream of filler tobacco leaves or particles, a vertical magazine having an open receiving end for receiving lengths cut from said tobacco, a movable platform positioned to travel to and from tobacco receiving position adjacent said mechanism where it receives a length to be cut from said stream, and discharge position adjacent said magazine where said length is discharged into said magazine, means for compressing said tobacco in said magazine, means for separating a section of uniform volume from said compressed tobacco, means for ejecting said section from said magazine with the leaves (or particles) of each length substantially arranged (or positioned) relatively to each other as originally cut from said stream, and means for varying the thickness of tobacco sections separated from the tobacco in said magazine.

8. In a cigar machine, the combination with a long filler tobacco feeding mechanism for feeding a stream of tobacco, of a pivoted platform movable into alignment with said mechanism for receiving predetermined lengths of tobacco to be cut from said stream, a magazine having an open tobacco receiving end, means for moving said platform to a position adjacent said magazine, a length receiving member closing said end when said platform has been moved adjacent said magazine, means for withdrawing said member to allow lengths positioned thereon to be ejected into said magazine, and means for ejecting tobacco lengths on said platform into said magazine.

9. In a cigar machine, the combination with a device for feeding a stream of tobacco leaves or particles, of means for severing predetermined lengths from the stream, a magazine positioned to receive said lengths in superposed relationship, means for conveying said lengths to said magazine with the leaves (or particles) of each length substantially arranged (or positioned) relative to each other in a planar arrangement corresponding to their arrangement when originally cut from said stream, said magazine comprising spaced walls, a movable bottom support yieldingly mounted for movement in said magazine, a tamping member movably mounted above said magazine and adapted to move into said magazine to compress said lengths of tobacco in said

magazine to form a column of tobacco of uniform density therein, means for separating sections from said column while under compression, and means for ejecting said sections from said magazine.

10. A cigar bunch machine comprising a magazine for tobacco having spaced walls, an open top end and bottom end, a yieldingly mounted support closing said bottom end and supporting a column of tobacco fed into said magazine, a closure member closing said top end, means for depositing charges of tobacco upon said member, and means for withdrawing said member to allow said tobacco charge to enter said magazine.

11. In a cigar bunch machine, a magazine having spaced vertical walls, an open top end and a bottom end, a movable support closing said bottom end and supporting a column of tobacco in said magazine, a closure member for the top end of said magazine, means for feeding predetermined lengths of filler tobacco onto said member, means for compressing said tobacco lengths upon said member, means for raising said support to bring the column of tobacco up against the underside of the member, means for withdrawing said member so that the tobacco positioned thereon may assemble with the tobacco in said column, means for lowering said support and compressing means simultaneously to position said column in charge separating position, while maintaining said column under compression, and means for separating thin charges of tobacco from said column.

12. In a cigar bunch machine, a device for forming predetermined lengths of long filler tobacco, a magazine for holding a column of said tobacco, means for intermittently feeding said lengths into said magazine, means for separating a thin section from said column, said means comprising a reciprocating tobacco engaging separating plate, a knife mounted on said plate, means to reciprocate said plate to advance said knife into said magazine to separate said section from said column and means for moving said knife relative to said plate during the advance of said plate into said magazine.

13. In a cigar bunch machine, a magazine for supporting a column of long filler tobacco, means for feeding tobacco into said magazine, and means for separating thin layers of said tobacco from said column, said means comprising a horizontal reciprocating plate, a knife mounted in said plate, and means for moving said knife independently of the movement of said plate and transversely to the movement thereof as the latter advances into said magazine to separate a layer from said column.

14. In a cigar machine, a magazine containing a column of laminated layers of long filler tobacco leaves, means for compacting said column to a uniform density, said means comprising a yieldingly mounted bottom support plate mounted in the bottom of said magazine, a vertically reciprocating tamping plate mounted above the upper end of said magazine for vertical movement into and out of said magazine, means for placing a succession of lengths of tobacco in said magazine to form said column, means for moving said plate into engagement with each layer after it has been placed on other layers already in said magazine, and a lost motion connection controlling the movement of said tamping plate into said magazine, and means for separating thin sections of tobacco of a width several times in excess of their thickness from said column

while said tobacco is under compaction, said separating means being so constructed and arranged that it moves parallel with the leaf layers and separates said leaves without undue cutting as it enters said column.

15. In a cigar bunch machine, a magazine for supporting a vertical column of long filler tobacco, means for adding a succession of thin flat layers of tobacco to said column with the bottom of each succeeding layer resting on the top of a layer previously fed into said magazine, means for separating thin sections of tobacco from said column, said means comprising a horizontal reciprocatory plate movable into said magazine at right angles to the longitudinal axis thereof, means for holding said tobacco under uniform compression during said separation, and means for varying the thickness of the layer separated.

16. In a cigar bunch machine, a magazine for supporting a vertical column of long filler tobacco, means for adding tobacco in superposed layers to said column, means for separating thin sections of tobacco from said column, said means comprising a horizontal reciprocatory plate and an independently operated knife movable into said magazine at right angles to the longitudinal axis thereof, means for holding said tobacco under uniform compression during said separation, means for varying the thickness of the layer separated, a device for conveying separated layers from said magazine into a bunch forming mechanism, and means for effecting the discharge of said layer substantially intact into said mechanism.

17. In a cigar bunch machine, a magazine for supporting a column of long filler tobacco, means for adding tobacco to said column, means for separating thin sections of tobacco from said column, said means comprising a horizontal reciprocatory plate movable into said magazine at right angles to the longitudinal axis thereof, means for holding said tobacco under uniform compression during said separation, means for varying the thickness of the layer separated, the means for varying the thickness of said layers separated comprising a yieldingly mounted support for said tobacco column, a plate, a pin fixed to said support resting on said plate, and means for adjusting the position of said plate to control the location of said support.

18. In a cigar bunch machine, a movable platform, a feed mechanism for forwarding a stream of long filler tobacco leaves or particles onto said platform, means for cutting lengths from said stream on said platform, a vertical magazine for holding a column of filler tobacco formed of a series of superposed lengths, means for feeding lengths from said platform into said magazine in superimposed relation therein with the tobacco leaves (or particles) thereof substantially arranged (or positioned) relative to each other as originally cut from said stream, a horizontal segregating plate for separating a charge of uniform density from said column, and means for moving said plate into and out of contact with said column to separate said charge.

19. In a cigar bunch machine, a magazine containing a column of laminated long filler tobacco, means for forming thin layers from said tobacco in said column, said means comprising a horizontally movable segregating plate constructed to move between laminations and move said layer away from said column, a reciprocating knife

5 mounted in said plate, and means for reciprocating said knife during movement of said plate into and out of separating position for cutting those leaves which obstruct the movement of said plate.

20. In a cigar bunch machine, a vertical magazine containing a column of compressed laminated predetermined lengths of long filler tobacco leaves, mechanism for separating thin layers of tobacco along said laminations to form bunch charges of tobacco, said mechanism comprising a reciprocatory separating member movable between laminations to separate said layer, a knife mounted for cutting movement independent of and during the reciprocatory movement of said member, and means for imparting cutting movement to said knife to cut leaves which obstruct the movement of said mechanism.

15 21. In a cigar bunch machine, a vertical magazine containing a supply of long filler tobacco leaves, a separating plate arranged to enter said magazine and separate thin layers of tobacco from said supply as it moves into said magazine, a knife mounted at the front edge of said plate, 25 and means for reciprocating said knife as said plate advances into said column to cut leaves which do not separate as said plate advances.

22. In a cigar bunch machine, a vertical magazine containing a supply of long filler tobacco, a separating plate having a slotted forward edge arranged to enter said magazine and separate thin layers of tobacco from said supply, a knife mounted in said slot of said plate, and means for continuously reciprocating said knife transversely to the path of said plate as said plate advances into said column to separate said layer.

30 23. In a cigar bunch machine, a device for segregating thin layers of tobacco from a column of tobacco comprising a thin tobacco engaging plate, and a serrated knife movable independently of the movement of said plate mounted in the forward end of said plate, and means for imparting continuous cutting movement to said knife.

40 24. A device for separating thin sections from a column of laminated long filler tobacco comprising a thin plate arranged to engage said tobacco and move at right angles to the longitudinal axis of said column, and a knife mounted in said plate for movement relative thereto.

45 25. A device for separating thin layers from a column of tobacco comprising a movable tobacco engaging and separating plate provided with a slot adjacent one edge, a knife movably mounted in said slot, and means for moving said knife relative to the movement of said plate.

50 26. In a bunch machine, a magazine provided with a top and a bottom end, containing a vertical column of laminated long filler tobacco, means for feeding predetermined lengths of tobacco into said magazine and for maintaining said lengths substantially intact during the movement into said magazine including a device for receiving and positioning said lengths above said column, and means for moving said device horizontally out of said magazine to associate each last fed length with said tobacco in said column, means for placing said column under compression, and means for separating layers of uniform density and volume from said column while it is under compression, said separating means comprising a plate arranged to enter said magazine at a distance equal to the predetermined thickness of a layer above the bottom end of said magazine, and a knife at the forward end of said

60 70 75

plate arranged to cut tobacco tending to obstruct the movement of said plate while it is separating a layer of tobacco from said magazine.

27. In a bunch machine, a magazine provided with a top and a bottom end, a support closing said bottom end and supporting a column of long filler tobacco, means for feeding predetermined lengths of long filler tobacco into said magazine, mechanism for separating and removing from the magazine thin layers of tobacco of uniform density and volume, and means for adjusting the location of said support to vary the thickness of layers removed, said mechanism comprising a thin reciprocatory plate and independently reciprocable knife located at its advancing edge and movable with said plate into said magazine at a point the thickness of the layer of tobacco to be separated above said support for separating said layer.

28. In a cigar machine, the combination with mechanism for receiving bunch lengths of long filler tobacco of substantially predetermined width having the leaves thereof arranged in planes generally parallel to each other, of means cooperating with said mechanism to assemble said lengths in a vertical column with the leaves of the assembled lengths in generally parallel planes extending transversely of the column, and maintaining said lengths in said column under compression, a charge separator for separating bunch charges from said column, and means for holding the top and bottom of each separated charge and maintaining said charge under compression after removal from said column and prior to bunch formation.

29. In a cigar machine, the combination with devices for forwarding a stream of tobacco leaves arranged in a generally horizontal overlapping relation, a cutter arranged to cut said stream into bunch lengths from the forward end of said stream, means cooperating with said cutter to assemble said lengths in a column with the leaf webs of the assembled lengths generally parallel and with the leaves thereof in substantially the same position they occupied relatively to each other when originally cut from said stream, and a charge separator arranged to separate bunch charges from said column.

30. In a cigar bunch machine, a feed mechanism for feeding a stream of long filler tobacco, a vertically movable platform movable into alignment with said mechanism and arranged to receive a portion of said stream, means for cutting a predetermined length of tobacco from said stream on said platform, a magazine for holding a column of superposed lengths of tobacco, means for moving said platform to a point adjacent said magazine, means for ejecting said tobacco therefrom into said magazine, a segregating plate adapted to separate thin layers of tobacco from said column, a movable transfer device having relatively movable layer holding members for receiving said layers, means for moving said transfer from receiving to transfer position, and means for swinging the members of said device relative to each other to allow the charge layer therein to move as a layer onto the belt of a rolling apron where said layer is formed into a bunch.

31. In a cigar bunch machine, mechanism for separating thin layers of tobacco from a column of tobacco comprising a reciprocating carriage, a tobacco separating plate affixed to said carriage, a bar slidably supported in said carriage, spaced

arms fixed to the ends of said bar, cam followers mounted on said bar, stationary cams formed on said carriage, a knife cooperating with said plate supported at the ends of said bar, and means for reciprocating said bar substantially at right angles to the path of movement of said carriage between limits controlled by said cams and cam followers so that said knife cuts the tobacco of said column which does not separate as said 10 plate advances.

32. In a cigar bunch machine, mechanism for separating thin layers of tobacco from a column of tobacco comprising a reciprocating carriage, a tobacco separating plate having a slot in the 15 front edge thereof affixed to said carriage, a bar slidably supported in said carriage, spaced arms fixed to the ends of said bar, cam followers mounted on said bar, stationary cams formed on said carriage, a knife slidably mounted in said 20 slot supported at the ends of said bar, and means for reciprocating said bar between limits controlled by said cams and cam followers so that said knife moves into said column to separate a layer as said plate advances into said column.

33. A cigar machine comprising a tobacco feeding mechanism, a vertically movable support onto which tobacco is fed, means for severing predetermined lengths from said tobacco after it is fed onto said support, means for lowering said 30 support, a magazine for holding a plurality of superposed lengths of tobacco, means for feeding an additional length into said magazine from said lowered support, means for separating a uniform charge of tobacco from the bottom of 35 the tobacco in said magazine, a bunch charge receiving member, means for ejecting said separated charge from said magazine into said member, said member including a pivoted bottom plate positioned adjacent the bottom of said magazine and a top plate constituting a pocket swingably mounted with respect to said bottom plate, means for turning said member into position for discharging said charge, and means for 40 opening said plates to allow the charge to be discharged into a bunch rolling mechanism.

34. In a cigar machine, in combination, a vertical magazine for supporting a column of superposed lengths of tobacco, means for separating thin bunch charge layers from said column, a transfer device, a pusher movable at right angles to said column for ejecting said separated layers from said column into said device, means for swinging said transfer device into discharge position, and means for discharging the 50 contents of said device into a bunch forming mechanism, said device comprising a pair of relatively separable side plates and means for holding said plates apart when a layer is being delivered into said device.

35. In a cigar machine, a magazine for a column of long filler tobacco, a bottom support for said column, means cooperating with said support for compressing said tobacco to uniform density, a reciprocating layer separating device for separating thin layers of tobacco from said column while it is under compression, and a pusher movable relative to said device for ejecting 55 separated layers laterally from said magazine.

36. In a cigar machine, the combination with a device for feeding a stream of tobacco, of means for severing predetermined lengths from the stream, a vertical magazine positioned to receive said lengths in superposed relationship, means for conveying said lengths to said magazine, said

magazine comprising spaced walls, a movable bottom support yieldingly mounted for movement in said magazine, a compressing member movably mounted above said magazine and adapted to move into said magazine to compress said lengths of tobacco in said magazine to form a column of tobacco of uniform density therein, means for separating sections from said column while under compression, a movable transfer device, means movable beneath said separating member for placing separated sections into said device, and means to move said device to charge discharging position.

37. In a cigar machine, a vertical tobacco magazine for holding a column of superposed lengths of tobacco, means for compressing said tobacco to a uniform density, mechanism for separating thin layers of tobacco from said column and delivering said layers to a transfer device, said device comprising a pair of relatively movable members for receiving a layer of tobacco, means normally tending to close said members, a movable support cooperating with one of said members to hold said device open for receiving a charge, and means for moving said device to transfer a layer to discharging position for rolling into a bunch so constructed that said members move together to hold said layer in layer form therebetween during the transfer movement.

38. In a cigar bunch machine, a vertical magazine housing a column of superposed tobacco lengths, means for separating thin layers of tobacco from said column, means for ejecting said lengths from said column, a transfer device receiving said layers and transferring the same to a bunch rolling mechanism, said device including a pair of pivoted plates normally held in closed position, means carried by one of said plates for holding them open in layer receiving position, means for turning said device to grip a layer of tobacco fed between said plates, and means for opening said plates to allow said layer to move substantially intact into the loop of the Chianti belt of said bunch rolling mechanism.

39. In a cigar machine, a vertical tobacco magazine for holding a column of superposed lengths of tobacco, means for compressing the tobacco in said magazine to a uniform density, mechanism for separating thin sections of tobacco of bunch forming size from said column, a transfer device for transferring said sections to a bunch making unit, means for conveying said sections to said device, said device including a plurality of relatively separable members located adjacent said magazine, means for holding said members separated to receive sections from said magazine, means for moving said device to discharging position in the loop of the rolling apron of a bunch forming mechanism, means for moving said members together to grip said sections as said device is moving to said discharge position and means for separating said members in said loop to allow said sections to slide substantially intact into said loop.

40. In a bunch making machine, in combination, a bunch rolling table, a rolling apron provided with a loop for receiving bunch charges to be rolled into bunches, a transfer mechanism for transferring bunch charges into said loop comprising a pair of relatively separable flat plates for holding said charges in thin flat layers, means normally holding said plates in yielding contacting relationship, means for separating

said plates to receive a charge, means for moving said mechanism into said loop with one of said sides proximate a side of said loop, means for opening said plates to allow the charge to slide from said transfer, and means for raising said mechanism to leave said charge in said loop.

41. In a cigar bunch making machine, a bunch rolling mechanism, means for delivering thin bunch charges into said mechanism comprising a movable transfer pocket including a pair of flat plates hinged to one another at one end, means normally tending to hold said plates with their free ends together, means for separating said plates to receive a charge, means for moving said pocket to discharge position in said mechanism, means for separating said plates upon the arrival of said pocket at discharge position, for effecting sliding discharge from said pocket by movement of said pocket only into said bunch rolling mechanism whereby said charge of tobacco is disposed in substantially intact condition in said bunch rolling mechanism.

42. In a bunch making mechanism, a charge transfer device, comprising a pocket composed of a pair of relatively separable flat sides for holding bunch charges in thin flat layers, a lever supporting said pocket for movement to and from receiving and discharge position, means for separating said sides to receive a thin section of filler tobacco, means for closing said sides to grip said section during movement of the pocket from the receiving position, and means for opening said pocket at discharge position.

43. In a bunch making machine, the combination with a bunch rolling apron having a loop for the reception of bunch charges, of a device for conveying charges to said loop, comprising a pair of relatively separable flat side members for holding bunch charges in thin flat layers, a lever supporting said members, means for opening said members to receive a charge, means for closing said members to grip a charge as said device moves to discharge position, and a cam operable at said discharge position to open said side members to allow said charge to slide out of said device.

44. In a cigar bunch machine, the combination with means for forming thin wide wafer-shaped bunch charges having a width several times their thickness, a bunch rolling apron having a charge receiving pocket and a filler charge transfer for receiving said charge and delivering it edgewise against the bottom of said pocket, and apron operating means coacting with said apron to provide a pocket having a depth approximately equal to the width of said charge to receive the charge and coacting with said belt after a charge has been received to reduce the diameter of the apron pocket to cigar bunch diameter to form the charge to bunch cross-section.

45. The combination with means for vertically compacting a vertical column of superposed layers of long filler tobacco, of a horizontal member provided with a cutter for separating a charge from one end of said column, a charge transfer, a device for delivering the charge to said transfer, and means for actuating said member to sever the charge and maintain it in compacted condition while it is being delivered from said column to said transfer.

46. In a cigar machine, the combination with means for confining a plurality of superposed layers of tobacco cut to bunch length in a vertical column of laminated long filler leaves, of a

device for separating bunch charges from said column, including a reciprocating knife, means for moving said knife at right angles to the vertical axis of said column to cut said charges therefrom, and means for imparting a plurality of oscillations to said knife while said device is separating bunch charges from said column, said device being constructed and arranged to tend to cause said knife to move between the laminated leaves in said column and minimize the formation of small pieces of tobacco formed during the separation of a charge.

47. The combination with mechanism for feeding a stream of filler tobacco, of means for cutting a succession of bunch lengths from said stream, means for superimposing said lengths to form a column of tobacco, a device for compacting said column of tobacco to substantially a uniform density, and means for compacting each bunch length laterally prior to its delivery to said column.

48. The method of preparing long filler tobacco for formation into cigar bunch charges which comprises, forming a relatively narrow continuous stream of long filler tobacco leaves, cutting a succession of lengths of tobacco from the forward portion of said stream, laterally compacting each length in a horizontal direction after it has been cut from said stream, superimposing said lengths one upon another to form a vertical column of laminated long filler lengths, and separating bunch charges of tobacco from said column along a plane located at right angles to the longitudinal axis of said column.

49. The method of preparing long filler tobacco for formation into cigar bunch charges which comprises, laying long filler tobacco leaves in a restricted area to form a relatively narrow, continuous stream of overlapped long filler tobacco leaves of varying thickness from said overlapped long filler tobacco leaves, cutting a succession of lengths of tobacco from said stream, forming a column of laminated long filler lengths, transferring said lengths from said zone of cutting into said column, and maintaining the several leaves or particles positioned in a planar arrangement corresponding substantially to their original planar arrangement both during said transfer and when positioned in said column, and severing bunch charges of tobacco from said tobacco in said column along a plane located at right angles to the longitudinal axis of said column.

50. The method of preparing long filler tobacco for formation into cigar bunch charges which comprises, placing long filler tobacco leaves in overlapping relation to form an endless stream, successively cutting bunch lengths from said stream, assembling each length cut with the succeeding length to form a column wherein the top of one length is located in engagement with the bottom of the length next cut with the leaves being in a planar arrangement corresponding substantially to their original planar arrangement, compacting said column of tobacco to substantially uniform density, and then separating bunch charges of tobacco from said column.

51. A device for separating sections of tobacco from a column of tobacco comprising, a tobacco engaging and separating plate, a knife movably mounted on said plate, and means for moving said knife with a compound reciprocatory and oscillatory movement during the operation of said plate.

52. The combination with means for feeding a continuous stream of long filler tobacco leaves, and a cutter for severing bunch lengths of tobacco therefrom, of means for superimposing said lengths on one another to form a column of lengths of laminated long filler leaves, means for compacting said column, a device for separating bunch charges from said column, comprising a knife positioned with its cutting edge substantially parallel with the longer dimension of the superimposed lengths of tobacco forming said column, and means for moving said knife with a compound reciprocatory and oscillatory movement during the operation of said device to separate said charges, said device being constructed and arranged to tend to cause said knife to move between the laminated leaves in said column and minimize the formation of small pieces of tobacco formed during the separation of a charge.

53. The method of forming cigar bunch charges which consists in forming a stream of overlapping long filler tobacco leaves of substantially predetermined width, subject to variations in thickness, cutting a succession of cigar lengths from said stream, assembling each length cut with the succeeding length to form a column wherein the top of one length is located in engagement with the bottom of the adjacent length, and cutting bunch charges from said column in a plane approximately parallel to the bottom surfaces of said lengths, which charges are uniform in thickness despite possible variations in the thickness of the lengths from which the column is formed.

54. The combination with mechanism for feeding a stream of filler tobacco, of means for separating bunch lengths from said stream and superimposing them to form a column of tobacco, and a device for compacting said column to a predetermined density, said means including members coacting to compact the bunch lengths laterally to a predetermined width prior to delivery to said column and subsequent to the separation thereof.

55. The combination with means for separating tobacco sections from a source of supply and superimposing them in a column, of a device for compacting said column, and mechanism for separating bunch charges from said column, said means including members coacting to compress said sections laterally to a predetermined width prior to delivery to said column and subsequent to the separation thereof.

56. In a tobacco feed mechanism, a tobacco feed for feeding a stream of tobacco with leaves in overlapping relation, a cutting device for cutting lengths of tobacco from said stream advanced by said feed, a conveyor on which said lengths are located when cut from said stream and said conveyor is in receiving position so that leaves of each length are in overlapping relationship, a vertical tobacco magazine, means for ejecting said lengths from said conveyor into said magazine in superposed relationship and with the tobacco leaves positioned in a planar arrangement corresponding substantially to their original planar arrangement when said conveyor is in delivery position, a movable member for compressing tobacco in said magazine, and means for separating charges of tobacco from said magazine.

57. In a tobacco feed mechanism, a tobacco feed for feeding a stream of tobacco with leaves in overlapping relation, a cutting device for cut-

ting lengths of tobacco from said stream and advanced by said feed, a conveyor on which said lengths are located when cut from said stream and said conveyor is in receiving position so that leaves of each length are in overlapping relationship, a vertical tobacco magazine, means for ejecting said lengths from said conveyor into said magazine in superposed relationship and with the tobacco leaves positioned in a planar arrangement corresponding substantially to their original planar arrangement when said conveyor is in delivery position, a movable member for compressing tobacco in said magazine, means for separating charges of tobacco from said magazine, and means for stopping the tobacco feed when the tobacco in said magazine reaches a predetermined volume and density.

58. The method of making cigar bunches from a compressed column of vertically superposed lengths of long filler tobacco sufficient to form several bunches and with the leaf webs of the assembled lengths lying in generally parallel planes, which consists in separating thin layer charges, each having a width several times its

thickness from said column, transferring said charges substantially intact onto a bunch rolling surface where the charge is rolled into a bunch, and supporting the top and bottom of each charge and thereby maintaining the leaf arrangement of each separated charge substantially unchanged while it is being transferred.

59. The method of making cigar bunches which comprises forming a column of superposed laminations of long filler tobacco leaves sufficient to form a plurality of bunches with the leaf webs of the superposed laminations lying in generally horizontal planes, separating thin layers of a width several times their thickness from said column along a plane generally parallel to the plane of the laminations, removing the layer substantially intact from said column and transferring it to a rolling surface, supporting the top and bottom of each cut layer during its transfer in order to maintain the leaf arrangement thereof of substantially undisturbed and rolling each of said layers to form a cigar bunch.

JOHN F. HALSTEAD.
